BABY SWING

Charles J. Ouellet, West Haven, Conn.

Application June 6, 1938, Serial No. 212,212

4 Claims. (Cl. 155—65)

This invention relates to baby swings and has for the primary object the provision of an efficient and inexpensive device of the above stated character which may be easily kept in motion or swinging by a person's foot, allowing the person to read, sew or carry on other types of duties or work.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a swing constructed in accordance with my invention.

Figure 2 is a front elevation illustrating the device.

Figure 3 is a fragmentary side elevation illustrating a part of the operating means for imparting motion or swinging movement to the swing.

Figure 4 is a fragmentary front elevation illustrating said parts.

Figure 5 is a fragmentary side elevation illustrating a modification of my invention.

Referring in detail to the drawing, the numeral 1 indicates a supporting structure including a base 2 and uprights 3 secured thereto.

The uprights have journaled thereon a cross rod 4 to which are secured depending bars 5 carrying a baby chair or similar device 6. Secured to the rod 4 paralleling one of the bars 5 is a lever 7 provided with a pin 8 operating in a slot 9 of an arcuately curved lever 10. One end of the lever 10 is journaled on a bracket 11 carried by the supporting structure 1. The other end of the lever 10 has pivoted thereto a connecting rod 12. A foot pedal 13 is pivotally mounted on the base 2 and has the connecting rod 12 pivoted thereto, as shown at 14. The device described may be easily kept in motion or swinging by a person's foot operating the foot pedal 13 leaving the person free to carry on other duties.

Referring to the modification shown in Figure 5, one of the members 5 has fixed thereon a segmental gear 15 meshing with a segmental gear 16 which includes a curved arm 17 adapted to be connected to the rod 12. The gear 16 is journaled on the supporting structure 1. The operation of the foot pedal through the gears 15 and 16 will impart swinging movement to the device.

55 What is claimed is:

1. A baby swing comprising a supporting structure, a rod journaled on said structure, a swing structure secured on said rod, a lever secured on said rod, an arcuately curved lever pivoted on the supporting structure and having a pivotal and slidable connection with the first-named lever, a foot pedal pivotally mounted on the supporting structure, and a rod connecting the foot pedal to the second-named lever.

2. A baby swing comprising the combination of a supporting structure, a rod journaled on said structure, spaced bars fixed to said rod, a swing secured to the said spaced bars, a bracket carried by the said supporting structure and extending inwardly therefrom, an arcuately curved lever pivotally mounted on the said bracket and having an elongated slot, levers carried by said rod and in appressed relation with the outer sides of the spaced bars, and a pin carried by one of the said last-mentioned levers and received in the elongated slot of the said arcuated lever.

3. A baby swing comprising the combination of a supporting structure, a rod journaled on said structure, spaced bars fixed to said rod, a swing secured to the said spaced bars, a bracket carried by the said supporting structure and extending inwardly therefrom, an arcuately curved lever pivotally mounted on the said spindle and having an elongated slot, levers carried by said rod and in appressed relation with the outer sides of the spaced bars, a pin carried by one of the said last-mentioned levers and received in the elongated slot of the said arcuated lever, a foot pedal pivotally mounted on the said supporting structure, and a connecting member joining the end of the arcuately curved lever and the said foot pedal.

4. A baby swing comprising the combination of a supporting structure, a rod journaled on said structure, spaced bars fixed to said rod, a swing secured to the said spaced bars, a foot pedal pivotally mounted on the said supporting structure, levers carried by the said rod and in appressed relation with the outer sides of the spaced bars, an arcuately curved lever pivotally attached to the said supporting structure and having a slidable and pivotal engagement with a shank projecting laterally from one of the said first-mentioned levers, and a connecting member joining the end of the arcuately curved lever and the said foot pedal, in a manner whereby a pendulous movement may be imparted to the said swing structure.
